DESIGN.

—o—
L. CLÉMENCET.

SURFACE ORNAMENTATION OF WALLS.

No. 18,562.

Patented Aug. 28, 1888.

UNITED STATES PATENT OFFICE.

LOUIS CLÉMENCET, OF WEST HOBOKEN, NEW JERSEY, ASSIGNOR TO
WARREN, LANG & CO., OF NEW YORK, N. Y.

DESIGN FOR THE SURFACE ORNAMENTATION OF WALLS.

SPECIFICATION forming part of Design No. 18,562, dated August 28, 1888.

Application filed August 3, 1888. Serial No. 281,891. Term of patent 3½ years.

To all whom it may concern:

Be it known that I, LOUIS CLÉMENCET, a citizen of the United States, residing at West Hoboken, Hudson county, State of New Jersey, have invented a certain new and useful Design for Hangings, of which the following is a specification, reference being had to the accompanying photograph, which forms a part hereof.

10 The invention relates to a design to be placed upon the surface of paper or other suitable material used as hangings to decorate walls, &c.

15 The accompanying photograph is a face view of part of a hanging, showing my complete design applied thereto. This design will generally be repeated many times; and it will be observed that in the photograph the extreme lower part contains a repetition of the upper part.

20 The design consists of a combination of forms representing flowers, leaves, and branches. The branches are intertwined and follow an

undulating line in general contour. The flowers are arranged in bunches, and these bunches are alternately placed to the right and left of the branches. Some of these bunches of flowers are large and form prominent parts of the design, while the rest of the bunches are smaller and are placed at intervals between the larger bunches and leaves. The leaves are generally 25 long and pointed, and are irregularly interspersed between the flower-bunches, being supported on short stems projecting from the branches. They are of different sizes and are shown in various positions.

30 35 What I claim as new, and desire to secure by Letters Patent, is—

The design for hangings, consisting of the design substantially as shown.

LOUIS CLÉMENCET.
